(Continued)

Primary Examiner — Shawn T Gingrich(74) *Attorney, Agent, or Firm* — Keating & Bennett, LLP(57) **CLAIM**

The ornamental design for a connector, as shown and described.

DESCRIPTION

FIG. 1 is a top, front, and left side perspective view of a connector showing our new design;
 FIG. 2 is a top, back, and right side perspective view thereof;
 FIG. 3 is a top, front, and left side perspective view thereof;
 FIG. 4 is a bottom, back, and left side perspective view thereof;

FIG. 5 is a back view thereof;

FIG. 6 is a front view thereof;

FIG. 7 is a left side view thereof;

FIG. 8 is a right side view thereof;

FIG. 9 is a top view thereof;

FIG. 10 is a bottom view thereof;

FIG. 11 is a close-up top, front, and left side perspective view of a connector showing our new design; and,
 FIG. 12 is a close-up bottom, back, and left side perspective view thereof.

The broken lines in the drawing views are included to show unclaimed subject matter only and form no part of the claimed design.

1 Claim, 12 Drawing Sheets(56)
